UNITED STATES PATENT OFFICE.

FRANCIS E. SWIFT, OF DAYTON, OHIO.

HEATING AND VENTILATING APPARATUS.

1,115,614.

Specification of Letters Patent.

Patented Nov. 3, 1914.

Application filed October 3, 1911. Serial No. 652,580.

To all whom it may concern:

Be it known that I, FRANCIS E. SWIFT, a citizen of the United States, residing at Dayton, in the county of Montgomery and State of Ohio, have invented new and useful Improvements in Heating and Ventilating Apparatus, of which the following is a specification, reference being had therein to the accompanying drawings.

This invention relates to new and useful improvements in apparatus for heating and ventilating purposes by the use of a combined steam and hot water sectional boiler and ordinary indirect radiators and ventilating apparatus.

The object of the invention is to provide an apparatus which is adapted to the various kinds of fuel and particularly to the cheaper fuel known as slack and also to provide means to supply each radiator with fresh cold air from the outside and ventilate by taking the cooler and foul air (which naturally settles to the floor) and sending it up the smoke flue as hereafter described.

A further object of my invention is to provide an apparatus with two separate and distinct furnaces, one on either side of a series of down-draft flues which are arranged to receive the products of combustion, hot gases and smoke from both furnaces at the same time or separately at different times. This apparatus is adapted to be operated economically in milder weather, such as prevails in the fall or early spring, and also may be run to its full capacity by firing both furnaces during the extremely cold weather, thereby insuring a proper degree of heat during the entire period when heat is required to greater or less degree.

A further object of the invention is to provide a furnace in which different fuel may be used at one and the same time, for example, soft and hard coal, coal and wood, coke and wood, or gas in one side and any kind of fuel in the other, at the same time.

I attain these objects by the device here described and shown in the accompanying drawings in which:

Figure 1 is a front elevation of my improved combined steam or hot water boiler and ventilating apparatus. Fig. 2 is a cross sectional view on the line A A of Fig. 3. Fig. 3 is a longitudinal sectional view on the line B B of Fig. 1. Fig. 4 is a longitudinal sectional view on the line C C of Fig. 1. Fig. 5 is a longitudinal view similar

to Fig. 3 showing the radiators and fresh and foul air attachments.

The reference letters are pertaining to the fresh air supply distributing tubes and radiators.

D designates my patented ventilating apparatus, patented Jan. 31, 1911—No. 983197, which projects outside of the wall and is connected with E which designates the main conductor pipe which varies in size according to the number of radiators to be supplied.

F designates the branch pipes leading to the distributing chambers.

G designates the chambers which are supplied with a regulating device which can be set to suit weather conditions.

H designates the radiators which may be of any desired type and connect with the boiler in the usual way.

I designates the foul air ducts which take the cooler and foul air out of the room and send it up the smoke flue, as hereafter described.

The same characters represent the same parts in the different views.

1 designates the base of the apparatus.

2 designates the front section of the boiler.

3 designates the rear section of the boiler.

4 designates the intermediate sections of the boiler which vary in number according to the capacity of the boiler.

5 designates the grate bars, the frame of which rests on the supports which are cast on the front and rear sections of the boiler.

5^a designates the gas burner and supply.

6 designates the ash pits.

7 designates the fire box and combustion chambers which are constructed slightly wider at the bottom than at the top which allows the burning fuel to feed down as it is being consumed thus avoiding the objectional feature of the fuel hanging in the top portion of the furnace which causes the fire to go out before it is all consumed.

8 designates the throats leading from the combustion chambers into the smoke box.

9 designates the down draft flues.

When the damper is closed the smoke and hot gases must travel horizontally in a flue toward the front of the apparatus then perpendicularly through a descending flue into a second horizontal flue which leads to the rear end of the apparatus; then again descending in a perpendicular flue which

allows it to enter a third horizontal flue and travel to the front of the apparatus when it again descends through a throat in a perpendicular direction into the lower flue and again returns to the rear end of the apparatus and is discharged into the ascending flue 9^a which is connected with the smoke box 10, and which is provided with a damper near the top which is set to regulate the draft and amount of suction for the foul air suction discharge.

10^a designates the suction flue to which the foul air ducts 1 are connected. This suction flue is constructed of cast iron and is 15 in connection with the ascending flue 9^a which conducts the smoke to the smoke box to which is connected a smoke pipe 11. Both the ascending flue and the foul air suction flue are cast in one piece with a partition between them. The manner of the construction of this double flue causes an extraordinary draft on the foul air ducts; viz. the heated partition in properly proportioned sizes and the deflecting damper 25 near the top of the ascending flue 9^a causes an intermingling discharge of both flues into the smoke box: hence a very strong suction on the foul air ducts.

12 designates the water chambers as 30 shown on Figs. 2, 3, 4, and 5.

12^a designates the flow pipes.

12^b designates the return pipes.

13 designates the water front which forms the front of the fire box and is designed to 35 heat water for domestic or other uses.

14 designates the water pipes which are connected with the water fronts 13.

15 designates the sliding overdraft dampers.

40 16 designates the sliding regulating dampers.

17 designates the direct damper.

18 designates the foul air damper.

19 designates the check draft door.

45 20 designates the furnace feed doors.

21 designates the ash pit doors.

22 designates the ash pit draft doors.

23 designates the clean out doors.

50 24 designates the lugs which are cast on each section for the purpose of bolting them together.

25 designates the short assembling bolts which are used to hold the packing in place and assemble the boiler until the expansion rods are installed and rigidly tightened.

55 26 designates the expansion and contrac-

tion rods which are put in place after the boiler is assembled, tightened, and the short assembling bolts loosened. These rods expand and contract with the heating and cooling of the water in the boiler which insures the packing or gaskets in joints between sections to stay tight. In practice I have found that rods so immersed in the hot water or generated steam give entire satisfaction and fill a long felt want where packing is used between the section. The rods 26 so placed, as shown in these drawings, will assume the temperature of the water or steam and begin to expand evenly or to cool as the liquid so cools. In this way there is no possibility of damage being wrought to the packing by sudden heating or cooling which does damage to the joints which are assembled with suitable packing.

While I have herein shown and described one form of my invention I wish it to be understood that this particular form has been chosen for the purpose of illustration and that I do not wish to be limited to the 8 details of construction shown and described, for obvious modifications will occur to a person skilled in the art.

What I believe to be new and what I desire to secure by Letters-Patent is—

1. In an apparatus of the class described, parallel spaced fire boxes, a smoke box, damper controlled throats leading from said fire boxes to said smoke box, zigzag down draft flues including a plurality of horizontal vertically spaced flues, connected alternately at their front and rear ends, an ascending flue connecting the rear end of the lowermost horizontal flue with said smoke box, a damper at the top of said ascending flue and a smoke pipe connected with said smoke box.

2. In an apparatus of the class described, the combination of a series of down draft flues arranged to receive the products of combustion, fire boxes arranged on either side of said down draft flues, and means for directing into said flues the products of combustion from both fire boxes either simultaneously or at different times.

In testimony whereof, I affix my signature in presence of two witnesses.

FRANCIS E. SWIFT.
